United States Patent Office

Des. 214,728
Patented July 22, 1969

214,728

WHEEL CENTER UNIT

Donald J. Reid, Pleasant Ridge, Mich., assignor to Kelsey-Hayes Company, Romulus, Mich., a corporation of Delaware

Filed Sept. 23, 1968, Ser. No. 13,656

Term of patent 14 years

Int. Cl. D12—14

U.S. Cl. D14—30

FIGURE 1 is an elevational view of a wheel center unit showing my design;

FIGURES 2 and 3 are sectional views thereof taken along the lines II—II of FIGURE 1 and III—III of FIGURE 2, respectively; and

FIGURE 4 is a perspective view thereof on a reduced scale.

I claim:

The ornamental design for a wheel center unit, substantially as shown and described.
